UNITED STATES PATENT OFFICE.

OLE ELLEFSEN, OF BURNSIDE, GLASGOW, SCOTLAND, ASSIGNOR TO ELECTRIC CONTROL LIMITED, OF BRIDGETON, GLASGOW, SCOTLAND.

ELECTRICAL ALTERNATING-CURRENT RELAY.

Application filed August 26, 1921. Serial No. 495,547.

(GRANTED UNDER THE PROVISIONS OF THE ACT OF MARCH 3, 1921, 41 STAT. L., 1313.)

To all whom it may concern:

Be it known that I, OLE ELLEFSEN, a subject of the King of Norway, residing at Lingard, Blairbeth Road, Burnside, Glasgow, Scotland, have invented new and useful Improvements in or Connected with Electrical Alternating-Current Relays, for which applications have been filed in Great Britain, May 10, 1918; France, June 25, 1920; Germany, July 1, 1920; Belgium, June 24, 1920, and of which the following is a specification.

This invention relates to electrical alternating current relays for use in switch control systems of the character in which the circuit, containing the relay coil, is energized by the closing of a switch actuated by means of an electro-magnet, the function of the relay being to retain separated contacts of an auxiliary circuit (a resistance switch operating circuit, for instance), in order to prevent the auxiliary circuit from being completed until the current in the relay coil circuit has subsided to a predetermined extent when the resistance may safely be reduced.

In systems of this character, hereinafter referred to as of the character defined, the relay coil has been arranged to act upon a core (or armature) which normally tends to move outwards to complete the auxiliary circuit, but which is held in its inward position, in which the contacts of the auxiliary circuit are separated, while the switch is open, by mechanical means associated with the switch, which mechanical means in the process of closing the switch are withdrawn. Thus it will be recognized that the process of releasing the relay core is in operation while the process of closing the switch is in progress, so that outward movement of the relay core may occur before the switch is actually closed, which brings the relay coil into action for retaining the relay core in its inward position, if the closing of the switch is sufficiently slow and the movement of the relay core and parts connected therewith sufficiently rapid.

The improvements according to this invention relate to alternating current relays for use in switch control systems of the character defined, and consist in providing an initial action coil (or coils) arranged in

series with the coil (or coils) of a switch electro-magnet, so that the initial action coil comes into action with the coil of the switch electro-magnet to retain separated the auxiliary circuit contacts (which previously had been held separated mechanically when the switch was open), the initial action coil exerting a force which decreases as the current diminishes in the coil of the switch electro-magnet due to the alteration in the electro-magnetic conditions produced by the movement of the switch electro-magnet in the process of closing the switch.

An example of the application of this invention for the control of a three phase alternating current induction motor and slip rings will now be described.

In this case a main switch is provided comprising three contact levers which normally are maintained open by gravity or other force and closed by an electro-magnet having a coil for operating a core connected to the levers. This coil is arranged in a shunt circuit, for instance, in shunt across the mains, and in series in this shunt circuit is the initial action coil of the relay. For closing this shunt circuit a pilot switch is provided. The initial action coil is arranged to act upon a member having a core. The member is also adapted to be acted upon by the main coil or coils of the relay. The main coil or coils of the relay may, for example, be arranged as follows:—(1) In series with the rotor main circuit. (2) In parallel with a resistance or impedance in the rotor main circuit. (3) Across the slip rings. (4) Between a resistance or impedance cut-out switch and the permanent main circuit. (5) In series with the main stator circuit, or (6) in parallel with a resistance or impedance in the main stator circuit. With such arrangements, upon closing the pilot switch current passes through the coil of the switch electro-magnet and the initial action coil, the coil of the switch electro-magnet operates its core to close the main switch, and the initial action coil operates its core to hold the member of the relay in its inward position and contacts of an auxiliary circuit separated, and retain it there until the main switch is closed, which causes the main coil or coils of the relay to be energized and come into action to retain the

member until the current in the relay coils has subsided to the extent required to release the member, the release of which permits contacts to engage and complete the 5 auxiliary circuit which may contain the coil of a resistance cut-out switch.

In the accompanying drawings, Figure 1 is a diagram illustrating an application of this invention to a three phase alternating 10 current slip ring motor.

Figure 2 is an inverted plan and Figure 3 is a side elevation partly in section illustrating relay apparatus constructed according to this invention.

15 In Figure 1, A designates a motor, B the mains, C the main switch, D the stator leads, E the rotor mains, F main coils of the relay, G a resistance, J the coil of the main switch electro-magnet, K an initial action coil, H a member having cores for the main relay and initial action coils of the relay. In the diagram these cores are represented as being capable of moving together with the member H axially with reference to the axes of their respective coils. L a resistance cut-out switch coil, M a resistance cut-out switch, N a contact arm moving with the main switch C, and P a contact arm moving with the member H. 20 The member H is acted on by a spring R tending to draw it into its switch closing position. Provision is also made, but not indicated in this diagram, whereby when the main switch C is open the member H is held in its inward position by mechanical means operating with the switch. The coil J and initial action coil K are in series in a shunt circuit across the mains, which is closed by a pilot switch S.

40 The operation of this system is as follows:—Upon closing the pilot switch S the coils J and K are energized, whereupon the initial action coil K by acting on its core retains the member H in its inward position. 45 The switch C is closed by the action of the coil J. When the switch C has closed, the motor circuit and the main coils F F of the relay are energized and operate to retain the member H in its inward position. 50 In the process of the switch C closing the current in the circuit containing the coils J and K decreases due to the entry of the core of the switch magnet into its coil J, with the result that the main coils F F of the relay come into action for retaining the member H in its inward position when the energy of the initial action coil K has considerably diminished. Subsequently, when 55 the current in the main coils F of the relay has diminished (as the motor A speeds up) to the degree required to permit the spring R to operate, the member H is released and the arm P is brought into contact with the

arm N and thereby completes an auxiliary circuit containing the coil L which then operates to close the switch M and short circuit or cut out the resistance G.

The constructional example shown at 70 Figures 2 and 3 will now be described. In this construction 1 designates a base upon which are mounted three main coils F and one initial action coil K of the relay. Three cores 2, arranged one within each of the 75 coils F, are carried by a member consisting of an arm 3 mounted to turn about an axis at 4. A contact 6, carried by the arm 3, is adapted to complete an auxiliary circuit containing the coil of an electro-magnet of 80 a resistance cut-out switch to be actuated, by making contact with contact 7. The arm 3 is acted on by a spring R which tends to turn the arm into its outward position and move contact 6 into contact with 7. In this construction, T designates an arm carried by the main switch, the full lines denoting the position of the arm T when the main switch is closed, and the dotted lines indicating the position when open. In the 85 open condition of the main switch the arm T operates to separate and maintain contact 6 separated from 7. It will be noted that the middle main coil F and the initial action coil K of the relay are arranged to 90 act upon the same core 2, but in other forms of construction a core or armature acted on by an initial action coil is not necessarily also acted on by a main coil of the relay.

95 For controlling the cut-out or short circuiting of successive steps of resistances, there may be provided a relay apparatus for each resistance to be cut-out, the arrangement being such that the initial action coil of each relay, succeeding the first, is arranged each in series with the coil of an 100 electro-magnet for operating a cut-out switch for the preceding resistance.

105 I claim:—

110 1. A system of switch control comprising an alternating current relay, a switch actuated by means of an electro-magnet and an auxiliary circuit, the relay comprising a main coil which is energized when the switch is closed, an initial action coil arranged in 115 series with the coil of the electro-magnet, a movable member having cores for the main and initial action coils of the relay, auxiliary circuit contacts, and means for holding the auxiliary circuit contacts separated 120 mechanically when the switch is open, for the purposes set forth.

125 2. A system of switch control comprising an alternating current relay, a switch actuated by means of an electro-magnet and an auxiliary circuit, the relay comprising a main coil which is energized when the switch is closed, an initial action coil arranged in series with the coil of the 130 electro-magnet, a movable member having cores

for the main and initial action coils of the relay, auxiliary circuit contacts, one carried by the movable member and an arm carried by the switch arranged to act upon the 5 movable member when the switch is open, substantially as set forth.

3. A system of switch control comprising an alternating current relay, a switch actuated by means of an electro-magnet and 10 an auxiliary circuit, the relay comprising main coils which are energized when the switch is closed, an initial action coil arranged in series with the coil of the electro-magnet, a movable member having cores for 15 the main and initial action coils of the relay, auxiliary circuit contacts, and means for holding the auxiliary circuit contacts

separated mechanically when the switch is open, for the purposes set forth.

4. A system of switch control comprising 20 an alternating current relay, a switch actuated by means of an electro-magnet and an auxiliary circuit, the relay comprising main coils which are energized when the switch is closed, an initial action coil 25 arranged in series with the coil of the electro-magnet, a movable member having cores for the main and initial action coils of the relay, auxiliary circuit contacts, one carried by the movable member and an arm 30 carried by the switch arranged to act upon the movable member when the switch is open, substantially as set forth.

OLE ELLEFSEN.
